DESIGN FOR A TEXTILE FABRIC OR SIMILAR ARTICLE

Sylvain Cusson, New York, N. Y., assignor to Cohn Hall Marx Co., New York, N. Y.

Application June 21, 1933. Serial No. 48,483

Term of patent 3½ years

To all whom it may concern:

Be it known that I, SYLVAIN CUSSON, a citizen of France, residing at 331 West 101 Street, New York, New York, have invented a new, original, and ornamental Design for a Textile Fabric or Similar Article, of which the following is a specification, reference being had to the accompanying drawing, forming a part thereof.

The figure is a plan view of a textile fabric showing my new design.

I claim:

The ornamental design for a textile fabric or similar article as shown.

In testimony whereof I have signed this specification.

SYLVAIN CUSSON.
